DESIGN FOR A CROSS

Horatio H. Farrington, Pearl River, N. Y.

Application January 9, 1939, Serial No. 82,261

Term of patent 14 years

To all whom it may concern:

Be it known that I, Horatio H. Farrington, a citizen of the United States, residing at Pearl River, county of Rockland, State of New York, have invented a new, original, and ornamental Design for a Cross, of which the following is a specification, reference being had to the accompanying drawing, forming part thereof.

The figure is a top plan view of a cross showing my new design.

The design has no substantial thickness and the opposite side is substantially plain.

I claim:

The ornamental design for a cross, as shown and described.

H. H. FARRINGTON.
